United States Patent Office.

ADOLPH ROESLER, OF WARSAW, ILLINOIS.

Letters Patent No. 70,362, dated October 29, 1867.

IMPROVEMENT IN MATCH-SAFES.

The Schedule referred to in these Letters Patent and making part of the same.

TO ALL WHOM IT MAY CONCERN:

Be it known that I, ADOLPH ROESLER, of Warsaw, in the county of Hancock, and State of Illinois, have invented new and useful Improvements in Match-Safes; and I do hereby declare that the following is a full and exact description of the same.

The nature of my invention consists in making a match-safe a little longer than twice the length of a common round match, with a partition, dividing it in the middle, and narrower at the lower or bottom end, which is left open, and below which a rod and slide are attached, for the purpose of thrusting the matches from the safe through openings on the sides provided with sharp-toothed spring-plates, which scratch and ignite the match.

To enable others skilled in the art to make and use my invention, I will proceed to describe its construction and operation, reference being had to the annexed drawings, making a part of this specification.

A is the match-safe. B is the partition which divides it into two equal parts, (see Figure I.) The safe A is made narrower at its lower or bottom end, which is left open, the opening being about as wide as the full thickness of a common round match. To both sides, at the lower end, are strips C C fastened, having holes through them, which are provided with one or two sharp-toothed spring-plates d d. A rod, E, surrounded by sliding tube F, is attached to strips C C, (or may otherwise be fastened to safe A,) below the holes and parallel with the lower or bottom end of safe A. Springs G G are fastened one on each side of safe A with one end, and with the other end to plate H, behind and extending a little above the safe, by means of which it may be fastened to the wall or any other suitable place. The springs G G are attached for the purpose of giving the safe a vibrating motion when operated, which tends to bring the matches regularly down to the slot; otherwise they would clog.

From the above description it will be seen that when matches are put in the safe A, and the slide F moved to one side, a match will fall down on rod E, ready to be pushed forward by slide F, through the opening between the toothed spring-plates d d, which scratch and ignite the match; at the same time another one will fall down on the other side ready for operation.

Having now described my invention, what I claim as new, and desire to secure Letters Patent, is—

Rod E and sliding tube F, in combination with the double safe A, provided with springs G G, or their equivalents, the whole arranged and operating substantially as described.
